(57) **CLAIM**

The ornamental design for a connector as shown and described.

DESCRIPTION

FIG. 1 is a top, right and front perspective view of a connector in accordance with a first embodiment of my new design;

FIG. 2 is a top, right and rear perspective view of the first embodiment;

FIG. 3 is a top plan view of the first embodiment;

FIG. 4 is a bottom plan view of the first embodiment;

FIG. 5 is a left side elevational view of the first embodiment; FIG. 6 is a right side elevational view of the first embodiment;

FIG. 7 is a front elevational view of the first embodiment; FIG. 8 is a rear elevational view of the first embodiment; FIG. 9 is a top, right and front perspective view of a connector in accordance with a second embodiment of my new design;

FIG. 10 is a top, right and rear perspective view of the second embodiment;

FIG. 11 is a top plan view of the second embodiment;

FIG. 12 is a bottom plan view of the second embodiment; FIG. 13 is a left side elevational view of the second embodiment;

FIG. 14 is a right side elevational view of the second embodiment;

FIG. 15 is a front elevational view of the second embodiment; and

FIG. 16 is a rear elevational view of the second embodiment.

FIG. 17 is a top, right and front perspective view of a connector in accordance with a third embodiment of my new design;

FIG. 18 is a top, right and rear perspective view of the third embodiment;

(Continued)

FIG. 19 is a top plan view of the third embodiment;
 FIG. 20 is a bottom plan view of the third embodiment;
 FIG. 21 is a left side elevational view of the third embodiment;
 FIG. 22 is a right side elevational view of the third embodiment;
 FIG. 23 is a front elevational view of the third embodiment;
 FIG. 24 is a rear elevational view of the third embodiment;
 FIG. 25 is a top, right and front perspective view of a connector in accordance with a fourth embodiment of my new design;
 FIG. 26 is a top, right and rear perspective view of the fourth embodiment;
 FIG. 27 is a top plan view of the fourth embodiment;
 FIG. 28 is a bottom plan view of the fourth embodiment;
 FIG. 29 is a left side elevational view of the fourth embodiment;
 FIG. 30 is a right side elevational view of the fourth embodiment;
 FIG. 31 is a front elevational view of the fourth embodiment; and,
 FIG. 32 is a rear elevational view of the fourth embodiment. Broken lines illustrate portions of the connector that form no part of the claimed design.
